UNITED STATES PATENT OFFICE

134,681

DESIGN FOR A CABINET FOR A SEWING MACHINE

James M. McKnight, St. Johns, Quebec, Canada,
assignor to The Singer Manufacturing Company,
Elizabeth, N. J., a corporation of New Jersey

Application October 31, 1942, Serial No. 108,653

Term of patent 14 years

To all whom it may concern:

Be it known that I, James McKnight, a citizen of the United States, residing at St. Johns, in the county of St. Johns and Province of Quebec, Canada, have invented a new, original, and ornamental Design for a Cabinet for a Sewing Machine, of which the following is a specification, reference being had to the accompanying drawing, forming a part thereof.

The figure is a perspective view of a cabinet for a sewing machine showing my new design.

I claim:

The ornamental design for a cabinet for a sewing machine, as shown.

JAMES M. MCKNIGHT.
